SUPERLOADING AUTOMATIC CHANGE-OVER
DEVICETheodore A. St. Clair, Pontiac, Mich., assignor to
Phillips Petroleum Company, a corporation of
Delaware

Application June 29, 1939, Serial No. 281,968

17 Claims. (Cl. 62—1)

The present invention relates to improvements in devices for automatically changing withdrawal connections from one source of high pressure gas to another upon decrease in pressure in the first

5 source. Liquefied petroleum gas, such as propane, butane, or a mixture of the two, is now being marketed extensively in tanks or cylinders. In making use of this liquefied gas for operating gas consuming appliances, such as domestic gas ranges, it is customary to provide the customer with two containers with some means of connecting them to a service line through a suitable arrangement of valves and pressure regulators. The usual 10 procedure is to use one of the cylinders as the active source of the gas supply, keeping the other cylinder as a reserve source until the first cylinder is exhausted. It is then necessary to cut off the exhausted source and establish connection with the reserve source. In prior practice, the valve on the active cylinder was opened while the valve on the reserve cylinder was kept closed. When the gas in the active cylinder became exhausted the valve on that cylinder was closed 15 and the valve on the reserve cylinder opened. The disadvantage of this system was that the customer had to go to the place where the cylinders were housed, usually outside, and change the valves each time one of the containers became depleted. Sometimes, a container became depleted at night or while the customer was not home and the result was that there was a cessation in the gas supply and all pilot lights were 20 extinguished. Recently there have been developed various systems equipped with so-called automatic valves, whereby upon the pressure in the active container becoming low, the vapor in the reserve container will be drawn upon but the valve must be reset for a second cycle. For 25 some time it has been desirable to produce a fully automatic change-over device that does not have to be previously set manually before it effects a change-over of withdrawal connections.

40 An important object of this invention is to provide an improved automatic change-over device that will be entirely automatic in its operation.

An additional object is to provide a novel indicating device to indicate which cylinder is being drawn upon to supply gas.

45 Other objects and advantages of the invention will appear in the following description and in the accompanying drawings. Referring to the 50 drawings:

Figure 1 is an elevation view showing the present invention used in connection with a two-drum system of liquefied gas distribution.

Figure 2 is a vertical cross-section through the center of a gas pressure regulator with provision 5 for superloading.

Figure 3 is a vertical longitudinal section through the automatic change-over device with associated parts in elevation.

Figure 4 is a vertical cross-section through the 10 center of the automatic change-over device with a second stage regulator in elevation.

Referring to Figure 1:

In Figure 1 reference numerals 1 and 1' indicate containers for liquefied gas. Gas pressure 15 regulators 2, 2' and conduits 3, 3' connect the containers for gas flow to the changeover device 4 from whence the gas goes to a second stage or system regulator 5 and then into the consumer's service line 6 which conveys the gas to the points 20 or utilization in gas consuming appliances. Conduits 7, 7' constitute part of the automatic change-over by conveying gas under pressure to regulators 2 as a superloading medium. An indicator is shown at 8 which operates in conjunction with the changeover device to show which 25 container is supplying the gas.

In Figure 2, a portion of a high pressure gas container is designated by reference numeral 1, while 12 represents the interior of this container. 30 An annular ring 13 having a shoulder 14 is attached to the container at 15. Ring 13 is tapped to receive a plug member 16 which is drilled and tapped to contain a valve 17 of the tire valve core type. Directly above the tire valve core stem 35 18 is a push-pin 19. Concentric with push-pin 19 is a tube 20 of sufficient diameter inside to provide an annular passageway 21. Concentric with tube 20 is a connector 22 having its lower portion externally threaded to engage an upper tapped 40 portion of plug member 16. Connector 22 bears against a shoulder on tube 20 forcing it against resilient gasket 23 and forming a gas-tight connection between tube 20 and plug member 16. 45 This valve and push-pin construction is substantially as disclosed in the co-pending application of Kenneth R. Lewis, Serial No. 201,581, filed April 12, 1938.

A regulator housing comprising a body 24 and 50 a cover 25 is provided with a flexible diaphragm 26 dividing the housing into two compartments, namely, a fluid compartment 27 and a loading compartment 28. Fluid compartment 27 is in communication with tube 20 and is provided with 55

an outlet port 29. Loading compartment 28 contains an expansion spring 30 and is provided with a port 31. Gas may be introduced through port 31 into the loading compartment. When the pressure in the loading compartment is above atmospheric, the regulator is herein described as being "superloaded."

In operation, the compression spring 30 exerts a pressure upon diaphragm 26. The resulting 10 downward thrust of the diaphragm is transmitted through push-pin 19 and valve stem 18 to the valve 17, actuating the same. High pressure gas in container 1 passes upwardly through the valve, in which its pressure is reduced by 15 throttling action, through the annular passageway 21 to the fluid compartment 27, and thence out of the fluid compartment through outlet port 29.

Should the pressure in the fluid compartment 20 become excessive, the diaphragm will be forced in an upward direction allowing the push-pin 19 to move upwardly, which in turn will release valve stem 18, allowing the valve 17 to close. The 25 valve will remain closed until the pressure in the fluid compartment drops to a point where the compression spring is enabled to force the diaphragm and plunger downward, reopening the valve. Constant withdrawal of vapor through outlet port 29 usually results in a throttling action 30 by valve 17 to maintain a constant pressure in fluid compartment 27.

Loading compartment 28 provides a means of changing the pressure in the fluid compartment 27 and hence the discharge pressure of the regulator. When compartment 28 is vented to the atmosphere, through port 31, a definite fluid pressure will be required in compartment 27 to force diaphragm 26 upward sufficiently to relieve valve stem 18 and allow valve 17 to close. This 40 pressure will be referred to hereinafter as the lower pressure level. If gas under pressure is introduced through port 31 to loading compartment 28 a super-atmospheric pressure will be built up in the loading compartment, superloading 45 the regulator. This super-atmospheric pressure will act on the top of diaphragm 26. Therefore, a higher pressure will be required in the fluid chamber to effect closure of valve 17, since the diaphragm must be forced upward against 50 the combined pressures exerted by the spring and the superloading medium. This discharge pressure will be referred to hereinafter as the higher pressure level.

The construction of the device, as shown, is 55 such that the assemblies on each side of body member 35 are structurally identical. To avoid confusion, the elements making up one of these assemblies will be described; primed reference numerals refer to like elements in the other assembly.

In Figure 3 is shown a housing, comprising a central body member 35, a left end member 36 and a right end member 36', is provided with 60 suitable diaphragms 37 and 37' between the body member and each end member forming service compartments 38 and 38' and control compartments 39 and 39'. End members 36 and 36' are shaped to provide valve compartments 42 and 65 42'. Service compartment 38 is provided with an inlet 40 in communication with conduit 3, and an outlet 41 having a raised nozzle or valve seat 44. Outlets 41 and 41' are in communication 70 with customer's service line through passageway 75 65 and second stage regulator 5. A passage 66 in

body member 35 intercepts passage 65 and is tapped at 67 to receive a coupling to a suitable pressure indicator not shown in the drawings. Control compartment 39 is in communication with conduit 3' through passage 45. Control 5 compartment 39 contains a compression spring 43 and a valve stem 46. Valve stem 46 which is square or hexagonal passes through a sleeve 47 of sufficient inside diameter to provide a passageway 52 between the valve stem and its internal 10 wall connecting control compartment 39 with valve compartment 42. Valve stem 46 where it contacts diaphragm 37 is not attached thereto. A plug member 48 contains a passageway 51 to receive tube 50. Passage 49 connects the valve 15 compartment 42 with conduit 7. Valve seats 53 and 54 are formed on sleeve 47 and plug 48 respectively. A plunger 55 is slidably mounted in compartment 42, the plunger being hexagonal in cross-section to allow flow of gas past it. This 20 plunger is provided with resilient disks or valve faces 56 and 57 which co-act with valve seats 53 and 54.

Indicating device 8 comprises a housing 60 vented to the atmosphere, a fan member 61 having 25 two blades 62 and 62' and being pivotally mounted on pin 63. Two nozzles 64 and 64', formed by extension of tubes 50 and 50' into housing 60, are set to direct any gas passing 30 through them against fan blades 62 and 62'.

In operation, a charged container 1 is connected with regulator 2. Loading compartment 28 is at atmospheric pressure, so regulator 2 discharges gas through outlet 29 at its lower pressure level. This gas passes through conduit 3 entering compartment 38 through inlet 40 and compartment 39' through inlet 45'. Pressure built up in compartment 39' will tend to seat diaphragm 37' on nozzle 44' and the spring 43' will 40 seat valve face 56' on valve seat 53', thereby effectively sealing off passages 41' and 52'. Passageway 51' is open to valve compartment 42', thereby establishing communication between conduit 7' and indicator 8. As pressure builds 45 up in compartment 38, diaphragm 37 will be forced to the left, compressing spring 43 leaving exit port 41 open so gas may flow to the customer's appliances. At the same time the action of valve stem 46 will force plunger 55 to the left 50 seating gasket 57 on seat 54, sealing off passageway 51'. Gasket 56 will be forced away from valve seat 53, opening annular passage 52, thereby establishing communication between conduit 3' and conduit 7.

Container 1' is now connected to regulator 2'. Loading compartment 28' is open to the atmosphere through conduit 7', valve chamber 42', tube 50', and indicator 8 which is vented to the atmosphere. Regulator 2' will discharge gas at 60 its lower pressure level. Gas from regulator 2' enters service compartment 38' through inlet 40' and control compartment 39 through passage 45'. Since passage 41' is sealed, gas will flow through compartment 39, annular passage 52, passageway 65 49, conduit 7 and into loading compartment 28 of regulator 2. As the pressure builds up in loading compartment 28 the discharge pressure of regulator 2 will increase to its higher pressure level due to the effect of superloading. This will 70 in turn increase the pressure in compartments 38 and 38' so there will be no change in the change-over mechanism. Container 1 will continue to supply gas to the appliances holding container 1' in reserve until container 1 is depleted. When 75

the pressure in container 1 drops to the point where it will no longer maintain a discharge pressure above the lower pressure level, diaphragm 37 will move to the right, allowing spring 43 to move valve stem 46 and plunger 55 to the right, closing off annular passage 52. This action will unseat gasket 57 from valve seat 54 and allow the small amount of compressed gas in loading compartment 28 to escape through conduit 7, valve compartment 42, and tube 50 to indicator 8 where it is directed through nozzle 64 against blade 63 throwing the fan member 61 to the right, indicating that a change-over has taken place. As the pressure in compartment 39' decreases, diaphragm 37' will move to the right to its intermediate position, opening exit port 41' and allowing gas to be withdrawn from container 1' to the customer's gas appliances. The pressure gauge, not shown in the drawings, will inform the customer that gas is being withdrawn from the reserve container.

When depleted container 1 is disconnected from the system conduit 3 and compartments 38 and 39' drop to atmospheric pressure. Since compartments 39 and 38' are at the lower pressure level, there is a pressure differential present across the diaphragms. Diaphragm 37 is merely pressed more firmly against nozzle 64 but diaphragm 37' is moved to the extreme right compressing spring 43'. At the same time the action of valve stem 46' will force plunger 55' to the right seating gasket 57' on seat 54', sealing off passageway 51'. Gasket 58' will be forced away from valve seat 53', opening annular passage 52', thereby establishing communication between conduit 3 and conduit 1'.

Container 1 is then replaced with a charged container, the charged container being connected to regulator 2. Loading compartment 28 is open to the atmosphere through conduit 7, valve chamber 42, tube 50, and indicator 8 which is vented to the atmosphere. Regulator 2 will discharge gas at its lower pressure level which in turn will superload regulator 2'. There will be no change take place in the change-over device and container 1 will therefore be held in reserve until container 1' is depleted, whereupon the change-over device will automatically make a change-over of withdrawal connections from container 50 1' to container 1, thus beginning a new cycle of operations, as described in detail above. The amount of gas discharged through nozzles 64 and 64' at the time of the change-over is very small and only suffices to throw the indicator back and forth.

While I have shown the diaphragm acting as a valve face and seating directly on the nozzle to form an outlet valve, it is apparent that various types of valves might be used to produce 60 the same result. It is also obvious that the two first stage regulators might be built integral with the change-over mechanism.

It is understood that the form of my invention described herein is by way of example of a preferred embodiment and that various changes may be made in size, shape and arrangement of parts without departing from the spirit of my invention as expressed in the claims.

I claim:

70 1. A system for storing and utilizing high pressure gas comprising a pair of containers for the gas, a consumer's service line, a conduit connecting each container to the consumer's service line, a gas pressure regulator associated with each conduit for controlling the pressure of the

gas drawn from the container connected to that conduit, each gas pressure regulator having a minimum outlet pressure, control means associated with each regulator for changing the outlet pressure and means actuated by change in 5 gas pressure in the other conduit for actuating the control means.

2. A system for storing and utilizing high pressure gas comprising a pair of containers for the gas, a consumer's service line, gas withdrawal 10 conduits connecting the containers to the service line, gas pressure operated means exposed to pressure differential between the gas withdrawal conduits, and valve means operable by the gas pressure operated means to selectively 15 connect one of the containers to the service line while disconnecting the other.

3. A system for storing and utilizing high pressure gas comprising a pair of containers for the gas, a consumer's service line, gas withdrawal 20 conduits connecting the containers to the service line, a valve controlling each withdrawal conduit, gas pressure operated means operating the valves, a second valve for each conduit between the first claimed valve and the service line, and 25 a second gas pressure operated means for controlling the second valve in response to pressure differential between the outlet sides of the first claimed valves.

4. A system for storing and utilizing high pres- 30 sure gas comprising a pair of containers for the gas, a consumer's service line, gas withdrawal conduits connecting the containers to the service line, a valve controlling each withdrawal conduit, gas pressure operated means operating the 35 valves to give a low pressure on the outlet side of the valves, control means associated with the gas operated means, operation of which results in a high pressure on the outlet side of the valve, a second valve for each conduit between 40 the first claimed valve and the service line, a second gas pressure operated means for controlling the second valve in response to pressure differential between the outlet sides of the first claimed valves, and a control conduit connecting 45 each control means with the outlet side of the other first claimed valve.

5. A system for storing and utilizing high pressure gas comprising a pair of containers for the gas, a consumer's service line, gas withdrawal 50 conduits connecting the containers to the service line, a valve controlling each withdrawal conduit, gas pressure operated means operating the valves to give low pressure on the outlet side of the valve, control means associated with the gas 55 operated means, operation of which results in a high pressure on the outlet side of the valve, a second valve for each conduit between the first claimed valve and the service line, a second gas pressure operated means for controlling the 60 second valve in response to pressure differential between the outlet sides of the first claimed valves, a control conduit connecting each control means with the outlet side of the other first claimed valve, a valve for each control conduit 65 operated by the second gas pressure operated means to operate the control means.

6. A system for storing and utilizing high pressure gas comprising a pair of containers for the gas, a consumer's service line, gas withdrawal 70 conduits connecting the containers to the service line, a changeover valve in each withdrawal conduit, and diaphragms for operating the change-over valves, one side of each second dia- 75 phragm being in communication with one with-

drawal conduit and the other side of the diaphragm with the other withdrawal conduit.

7. A system for storing and utilizing high pressure gas comprising a pair of containers for the gas, a consumer's service line, gas withdrawal conduits connecting the containers to the service line, a valve controlling each withdrawal conduit, regulator diaphragms having one side in communication with the withdrawal conduits for operating the valves to give a low pressure on the outlet side of the valve, gas compartments on the other side of the diaphragms, and control conduits connecting each gas compartment and the withdrawal conduit associated with the opposite regulator diaphragm.

8. A system for storing and utilizing high pressure gas comprising a pair of containers for the gas, a consumer's service line, a conduit connecting each container with the service line, a valve controlling each conduit and having an inlet side and an outlet side, a diaphragm for operating the valve to give a minimum pressure on the outlet side of the valve, loading means associated with the diaphragm to give a maximum pressure, second conduits connecting each loading means with the outlet side of the valve controlling the other conduit, valve means controlling the second conduits operative to close one second conduit and open the other.

30 9. A system for storing and utilizing high pressure gas comprising a pair of containers for the gas, a consumer's service line, a conduit connecting each container with the service line, a valve controlling each conduit and having an inlet side and an outlet side, a diaphragm for operating the valve to give a constant minimum pressure on the outlet side of the valve, loading means associated with the diaphragm to give a constant maximum pressure, and means operative on replacement of a depleted container with a container of the gas to actuate the loading means associated with the other container.

45 10. A system for storing and utilizing high pressure gas comprising a plurality of containers for the gas, a consumer's service line, a conduit connecting each container with the consumer's service line, a valve having an inlet side and an outlet side, a diaphragm having one side in communication with the outlet side of each valve, movement of the diaphragm serving to operate the valve, and means for applying the pressure present on the outlet side of another valve to the opposite side of the diaphragm.

55 11. A system for storing and utilizing high pressure gas comprising a plurality of containers for the gas, a consumer's service line, a conduit connecting each container with the consumer's service line, a valve having an inlet side and an outlet side, a diaphragm having one side in communication with the outlet side of each valve, movement of the diaphragm serving to operate the valve, a second conduit connecting the outlet side of another valve to the opposite side of each diaphragm and valve means in the second conduits operative in response to change in pressure to close all but one of the second conduits.

70 12. A system for storing and utilizing high pressure gas comprising a pair of containers for the gas, a consumer's service line, a conduit connecting each container with the service line, a valve controlling each conduit and having an inlet side and an outlet side, a diaphragm for operating the valve to give a constant minimum pressure on the outlet side of the valve, loading means associated with the diaphragm to give a

constant maximum pressure, and means for operating the loading means in response to increase in pressure at the outlet side of the other valve.

13. A system for storing and utilizing high pressure gas comprising a pair of containers for the gas, a consumer's service line, gas withdrawal conduits connecting the containers to the service line, a valve controlling each withdrawal conduit, regulator diaphragms having one side in communication with the withdrawal conduits for operating the valves to give a low pressure on the outlet side of the valve, gas compartments on the other side of the diaphragms, control conduits connecting each gas compartment and the withdrawal conduit associated with the opposite regulator diaphragm, and control conduit valves operated by the second diaphragms to disconnect either gas compartment.

14. A system for storing and utilizing high pressure gas comprising a pair of containers for the gas, a consumer's service line, gas withdrawal conduits connecting the containers to the service line, a valve controlling each withdrawal conduit, regulator diaphragms having one side in communication with the withdrawal conduits for operating the valves to give a low pressure on the outlet side of the valve, gas compartments on the other side of the diaphragms, control conduits connecting each gas compartment and the withdrawal conduit associated with the opposite regulator diaphragm, an exhaust conduit for each gas compartment, and an indicator associated with the exhaust conduits.

15. A system for storing and utilizing high pressure gas comprising a pair of containers for the gas, a consumer's service line, gas withdrawal conduits connecting the containers to the service line, a valve controlling each withdrawal conduit, regulator diaphragms having one side in communication with the withdrawal conduits for operating the valves to give a low pressure on the outlet side of the valve, gas compartments on the other side of the diaphragms, a change-over valve in each withdrawal conduit, second diaphragms for operating the change-over valves, one side of each second diaphragms being in communication with one withdrawal conduit and the other side of the diaphragm with the other withdrawal conduit, and control conduits connecting each gas compartment and the withdrawal conduit associated with the opposite regulator diaphragm.

16. A system for storing and utilizing high pressure gas comprising a pair of containers for the gas, a consumer's service line, gas withdrawal conduits connecting the containers to the service line, a valve controlling each withdrawal conduit, regulator diaphragms having one side in communication with the withdrawal conduits for operating the valves to give a low pressure on the outlet side of the valve, gas compartments on the other side of the diaphragms, a change-over valve in each withdrawal conduit, second diaphragms for operating the change-over valves, one side of each second diaphragm being in communication with one withdrawal conduit and the other side of the diaphragm with the other withdrawal conduit, control conduits connecting each gas compartment and the withdrawal conduit associated with the opposite regulator diaphragm and control conduit valves operated by the second diaphragms to disconnect either gas compartment.

75 17. A system for storing and utilizing high pressure gas comprising a pair of containers for

the gas, a consumer's service line, gas withdrawal conduits connecting the containers to the service line, a valve controlling each withdrawal conduit, regulator diaphragms having one side in communication with the withdrawal conduits for operating the valves to give a low pressure

on the outlet side of the valve, gas compartments on the other side of the diaphragms, an exhaust conduit for each gas compartment and an indicator associated with the exhaust conduits.

THEODORE A. ST. CLAIR.
